United States Patent Office.

EDMUND HOLDEN, OF HARTFORD, MICHIGAN.

Letters Patent No. 96,115, dated October 26, 1869.

IMPROVEMENT IN FILTERING-SECTIONS FOR TUBE-WELLS.

The Schedule referred to in these Letters Patent and making part of the same.

To all whom it may concern:

Be it known that I, EDMUND HOLDEN, of Hartford, in the county of Van Buren, and State of Michigan, have invented a new and useful Improvement in Filters for Tube-Well; and I do hereby declare that the following is a full and exact description thereof, reference being had to the accompanying drawings, and to the letters of reference marked thereon.

My invention consists of a peculiar novel construction and arrangement of two slotted tubes, one fitted within the other, and being removable.

In the accompanying drawings—

Figure 1 is a side view of my improved filter.

Figure 2 is a side view of the inner tube.

Figure 3 is a vertical section of the filter, showing both tubes in place.

The outer tube, seen in fig. 1, is a protection case, intended to be attached to the tube forming the well, by a screw coupling. The lower end of this tube is pointed, to penetrate the earth in the usual manner of tube-wells. This case is perforated with slots A, about one-twentieth of an inch wide, and from one-third to one-fourth the circumference of the tube in length, closely arranged, but without too much weakening the tube.

The inner tube, fig. 2, is slotted in a similar manner to the protecting-case, except that the slots are much narrower. This tube is the filter proper, and its external diameter is less than the internal diameter of the protection case, so that a small space shall be left

between them when the filter is inserted in the case, as seen in fig. 3.

The flanges B B, on the ends of the inner tube, fit the protecting-case, but so as to be easily removed for cleansing.

Both tubes may be constructed of brass, copper, galvanized iron, or other metal not liable to rust or corrode.

The size of the slots may be varied, to suit the nature of the soil in which it is to be used, and, if desirable, a wrapper of woven wire may surround the inner cylinder.

The manner of its operation is as follows:

The filter being placed in the protecting-case, and this attached to the well-tube, and driven into the ground till it reaches water, the water enters the tube through the protection case and filter, while sand and grit are excluded.

I do not broadly claim attaching a filter to tube-wells; but,

I claim and desire to secure by Letters Patent of the United States—

A filter, constructed of two concentric tubes of copper, brass, galvanized iron, or other metal not liable to corrode, the inner tube being easily removable for cleansing, all substantially as shown and described.

EDMUND HOLDEN.
